United States Patent

Des. 235,805
Patented July 8, 1975

235,805

STATIONERY EMBOSSE

Daniel E. McCue, Santa Barbara, Calif., assignor to
M & R Seal Press Co., Inc., Roselle, N.J.

Filed Sept. 14, 1973, Ser. No. 397,773

Term of patent 14 years

Int. Cl. D15—09

U.S. Cl. D64—10

FIG. 2.

FIG. 3.

FIG. 4.

FIG. 1 is a perspective view of a stationery embosser showing my new design;

FIG. 2 is a front elevational view;

FIG. 3 is a left elevational side view, the right side being a mirror image thereof; and

FIG. 4 is a rear elevational view.

I claim:

The ornamental design for a stationery embosser, as shown.
